UNITED STATES PATENT OFFICE.

FRANK C. KELLER, OF MILWAUKEE, WISCONSIN, ASSIGNOR OF TWO-THIRDS
TO EUGENE HABERMEHL AND HENRY W. THEIS, OF SAME PLACE.

FLUSHING-TANK.

SPECIFICATION forming part of Letters Patent No. 536,150, dated March 19, 1895.

Application filed May 19, 1894. Serial No. 511,803. (No model.)

To all whom it may concern:

Be it known that I, FRANK C. KELLER, of Milwaukee, in the county of Milwaukee and State of Wisconsin, have invented a new and 5 useful Improvement in Flushing-Tanks, of which the following is a description, reference being had to the accompanying drawings, which are a part of this specification.

My invention has relation to improvements 10 in flushing tanks.

The object is to provide a simple, inexpensive and noiseless construction, whereby the flushing may be accomplished either automatically or by hand, said construction 15 comprehend the employment of an eccentrically pivoted vessel within the flushing tank, which when turned upon its pivots, being automatically held in a tilted position until emptied of the contents, said vessel adapted, 20 after the flushing has been accomplished and during the re-filling operation, to return to its horizontal position, by reason of the water which is constantly discharged into the vessel creating an overbalancing weight, to one 25 side of the pivots, due to the eccentricity of said pivots.

The invention furthermore embraces as an object the adaptation of a receiving vessel of this character for use in all cases where a 30 large volume of water is needed for flushing purposes, as for instance in closets arranged in school houses, and other large buildings.

The invention consists of the devices and parts, or their equivalents, as hereinafter 35 more fully described and claimed.

In the accompanying drawings, Figure 1, is a transverse section of Fig. 2, the dotted lines indicating the position to which the tank is turned to the left. Fig. 2, is a longitudinal 40 section of my improved flushing tank. Fig. 3, is a longitudinal section of a modified form of tank. Fig. 4, is a plan view of Fig. 3. Fig. 5, is a detail end view of the inner receiving tank, showing one of the positions the same 45 assumes. Figs. 6 and 7 illustrate another modified form of my device, Fig. 6 being a transverse section of Fig. 7, and Fig. 7 being a longitudinal sectional view.

Like numerals of reference denote like parts 50 throughout the several views.

Referring, now, particularly, to Sheet 1 of

the drawings, the numeral 8 indicates an outer tank, which is shown as provided with an inner lining 9, having a rounded bottom provided with a centrally depending tube 10, to 55 the threaded end of which the outlet pipe is attached. Within the tank 8 is a receiving vessel, composed of straight end pieces 11, 11 and a circular bottom and sides 12, this circular portion, preferably, comprising two-thirds 60 of a complete circle. I do not wish, however, to be understood as limiting myself to this particular size, as it is obvious that variations may be made without departing from the spirit and scope of my invention. The dimensions given are preferable by reason of the fact that the greatest possible holding capacity is thereby afforded consistent with compactness of structure.

Projecting inward from arms 13, 13 secured 70 to the ends of the tank 8 are trunnions similar to 14 (see Fig. 2), said trunnions fitting freely in sockets 15 let into the inner receiving vessel. The point designated by the numeral 16, indicates the exact center of the circle described by the inner vessel. It will be noticed, however, that the trunnions are so located that the pivotal points of the inner vessel are to the right of, and slightly above, this central point, so that said inner vessel is eccentrically 80 mounted upon the trunnions.

Extending into the inner vessel at an obliquity is an inlet pipe 17, the end of which terminates a slight distance above the bottom of the vessel to the left of its pivotal points. 85

The upper edge of one side of the inner vessel is slightly lower than the edge of the opposite side. Running longitudinally along the side of the vessel near this lowered edge, and coextensive in length therewith, is a gutter or channel 18, which is formed by another supplemental outstanding wall 19, having an inclined bottom. This wall is provided centrally with a short elongated slot 20. Secured to the side of the inner vessel, immediately 95 below the channel 18, and also coextensive in length with said side of the vessel, is a tubular or hollow float 21. The form of device just described is adapted for flushing automatically and periodically. The water constantly 100 passes through the inlet pipe 17, and discharges into the inner receiving vessel. When

the water in this vessel rises to a level with the lower side of said vessel, a quantity of water sufficient to overbalance the vessel will flow over into the gutter or channel 18, and 5 give the vessel an initial turn upon its pivots. This slight turn will cause a larger quantity of water to flow into the channel, and thereby continue the turning of the vessel, the water constantly overflowing into the 10 channel. This turning continues until the vessel reaches the position shown in dotted lines in Fig. 1, when its further turning is prevented by the inlet pipe 17, which acts as a stop. It is obvious that a separate lug or 15 projection could be employed for the same purpose, but it is a convenient construction to have the pipe 17 serve the two-fold function of an inlet pipe and stop. When the vessel is thus at its limit of travel, the float 20 21 is submerged by the water in the bottom of the inner lining 19 which has not had a chance to escape through the outlet 10. Under these circumstances, the tendency of the 25 float is, of course, to rise to the surface of the water. This tendency naturally creates a pressure or power which would turn the tank farther around to the left were it not for the obstruction afforded by the inlet pipe 17. In this manner the vessel is held at its oblique 30 position until emptied of its contents, excepting perhaps a small amount of water which the inlet pipe empties into that portion of the vessel above the channel and float. The level of the water about the float of course gradually falls as said water rushes out of the outlet 10. Inasmuch as the pivotal points of the vessel are eccentric, or to the right of, and slightly above, the center of the circle described by the vessel, and consequently as the heaviest 35 40 part of the vessel is disposed at a point located approximately just above the channel and float, said vessel, when the water in the tank is thus emptying and falls below a certain level around the float, will move or turn 45 to the position shown in Fig. 5. In thus turning to this position, the gutter or channel necessarily scoops in a quantity of water. It is necessary, of course, to empty the water so scooped in by the channel or gutter, or else 50 said water would act as a retarding influence to the return of the vessel to its horizontal position. It is for this reason that I provide the slot 20 through which the water drains.

As soon as a certain volume of the water 55 which is being constantly fed to the vessel through the inlet pipe accumulates in the vessel, which, as will be understood, is still in the position last referred to, viz., in the position shown in Fig. 5, said vessel will, by reason of 60 the overbalancing weight of the water, cause the vessel to turn slowly and gradually toward the right of Fig. 1. As soon as it reaches a horizontal position its lowered edge contacts with the pipe 17, and of course all further turning is 65 prevented, by said pipe, thereby leaving the vessel at its former horizontal position ready to be automatically turned and dumped when

the water therein reaches a height sufficient to flow over the lower side edge of the receiving vessel, as first explained.

70

Figs. 3 and 4 show the adaptation of my device for use where a large volume of water is needed for flushing purposes, as for instance in the closets of school houses, large buildings, and in many other constructions where 75 a large volume of water is necessary to a successful flushing. In this form, I show one end of the long flushing tank 8 divided off at one end (Figs. 3 and 4) into a compartment 22 by means of a transverse partition 23. It 80 is obvious, however, that the long tank could terminate with the partition 23, and that the compartment 22 could be an independent or separate tank, arranged endwise to, and, if desired, secured to the longer tank. In practice, perhaps, this will be found the preferable 85 construction. Into the longer chamber 24 of the tank the inlet pipe 17' extends and discharges.

85

The numeral 25 indicates a siphon, the short 90 leg of which runs down alongside of the partition in the chamber 24 to a point near the bottom of said chamber, while the neck of the siphon extends over the partition 23, and the longer leg projects down into the chamber 95 22, and through the bottom of said chamber into the outlet 10.

A pipe 26 passes through the partition 23 at a point just below the neck of the siphon. The end of this pipe within the chamber or 100 compartment 22 is bent down at an angle into the pivoted receiving vessel. In the operation of this form of the device, the water from the source of supply is, of course, conducted by the inlet pipe 17' directly into the 105 longer chamber 24. When it reaches a certain height in this chamber, it will flow through the pipe 26, and discharge into the receiving vessel. As soon as this vessel is filled sufficiently to cause the water to run 110 over into the channel or gutter 18, the vessel is thereby turned upon its pivots, and the same operation as that explained in regard to the device illustrated, on Sheet 1 of the drawings takes place, the water which empties into the tank 8 passing to the outlet 10, and down the same to the long bowl (not shown) beneath. As this water flows down the pipe 10 a suction is created in the long 115 leg of the siphon which draws the water from 120 the chamber 25 up the short leg of the siphon and over the neck thereof, which, of course, immediately starts siphonage, and a continuous flow of the water from the chamber 25 to the bowl or whatever is desired to be flushed. 125 This continues until the water in the chamber 24 falls to such a level as to necessarily cause the siphonage to cease. The same operation again occurs when the chamber again fills up to the level of the end of the pipe 26. 130

Both of the constructions just explained, and illustrated upon Sheets 1 and 2 of the drawings, cover the application of my invention as an automatic flushing apparatus.

On Sheet 3 of the drawings is illustrated a form of construction in which the flushing is accomplished by the user. In this construction, an arm 27 projects up from the upper edge of one end of the receiving vessel, said arm being then extended outward over the end of the tank 8, and then downward, its end terminating at a point to one side of the eccentric pivots. To this end the pull cord 28 is attached. The inlet pipe 17" in this form has its end within the receiving vessel connected with a valve-casing 29, in which works a valve 30, the stem 31 thereof connected to a pivoted float-controlled lever 32. Another pipe 33 leads from the valve casing, and has its lower end terminating near the bottom of the receiving vessel.

In operation, when a person desires to flush the closet bowl, a pull is given to the cord 28, and the vessel turned to its full extent, or to the limit permitted by the inlet pipe 17". The water of course empties out of the vessel, and inasmuch as the float 21 is submerged the vessel is held thereby, for a time, in its oblique position, the same as in Fig. 1, notwithstanding the fact that the pull on the cord is discontinued, until the level of the water about the float lowers, and the overbalancing weight of the water accumulating in the vessel, causes the automatic return of said vessel, to its horizontal position. The level of the water in the receiving vessel, however, has been so lowered that the float-controlled lever 32 is lowered correspondingly, so that said lever is turned upon its pivot, and the valve thereby withdrawn from the end of the inlet pipe within the valve-casing 30. Water passing through the inlet pipe will, therefore, again fill the receiving vessel ready for another manipulation of the pull-cord. Of course when the water reaches a certain height in the receiving vessel, the float is raised sufficiently to close the inlet valve.

It is sometimes desirable, especially when the closet is located in close proximity to other rooms where the noise of the water could be heard, when the vessel is tilted its full extent, only to tilt the same slightly, and by continuing the pull on the cord, allowing only a small quantity of water to flush. Of course the moment the cord is released the overbalancing weight of the water will return the vessel to its horizontal position.

Having thus described my invention, what I claim, and desire to secure by Letters Patent, is—

1. In a flushing tank, the combination, of a tank, an outlet leading therefrom, an inlet pipe, and a pivoted vessel within the tank, into which vessel the inlet pipe discharges, said vessel provided at one side with a float, substantially as set forth.

2. In a flushing tank, the combination of a tank provided with an outlet, an inlet pipe, and a vessel pivoted in the tank, into which vessel the inlet pipe discharges, said vessel

provided along one side with a gutter or channel, substantially as set forth.

3. In a flushing tank, the combination, of a tank provided with an outlet, an inlet pipe, and a pivoted vessel into which the inlet pipe discharges, said vessel having one side lower than the other, with a channel or gutter running along said lower side, substantially as set forth. 75

4. In a flushing tank, the combination, of a tank provided with an outlet, an inlet pipe, and a pivoted vessel within which vessel the inlet pipe discharges, said vessel provided along one side with a channel or gutter, and below said channel or gutter with a float, substantially as set forth. 80

5. In a flushing tank, the combination, of a tank, an outlet leading therefrom, an inlet pipe, and a pivoted vessel, within which vessel the inlet pipe discharges, said vessel provided along one side with a gutter or channel having an elongated opening therein, substantially as set forth. 85

6. In a flushing tank, the combination, of a tank provided with an outlet, an inlet pipe, and an eccentrically pivoted vessel into which the inlet pipe discharges, said vessel provided along one side with a gutter or channel, substantially as set forth. 90

7. In a flushing tank, the combination, of a tank, an outlet leading therefrom, an inlet pipe, an eccentrically pivoted vessel into which the inlet pipe discharges, said vessel having the upper edge of one side lower than the corresponding edge of the opposite side, a channel or gutter along said lower side, said channel or gutter provided with an opening, and a float beneath the channel or gutter, said vessel adapted to be turned when the water therein overflows into the gutter or channel, the extent of turning being limited by the inlet pipe, substantially as set forth. 95

8. In a flushing tank, the combination, of a tank, an outlet leading therefrom, an inlet pipe, an eccentrically pivoted vessel within the tank, into which vessel the inlet pipe discharges, said vessel having one of its sides lower than the opposite side, a channel along said lower side, a float beneath said channel, and means for limiting the extent of the turning of the vessel in both directions, substantially as set forth. 100

9. In a flushing tank, the combination, of a tank, an outlet leading therefrom, an inlet pipe, and an eccentrically pivoted vessel within the tank, into which vessel the inlet pipe discharges, said vessel provided at one side with a float, substantially as set forth. 105

10. In a flushing tank, the combination, with an eccentrically pivoted vessel, provided along the upper edge of one side with a channel, of an inlet pipe leading to said vessel, substantially as set forth. 110

11. In a flushing tank, the combination, of a tank, an inlet pipe leading thereto, another tank or compartment adjoining or contiguous

to the first-named tank provided with an outlet, a vessel pivoted in the last-named tank, a pipe connecting the two tanks, and having its discharge end passing into the pivoted vessel, a siphon having its legs extending into the respective tanks, and means for turning the vessel when the water therein reaches a certain height, whereby the flow of said water down the outlet will start siphonage, substantially as set forth.

12. In a flushing tank, the combination, of a tank, an inlet pipe leading thereto, another tank or compartment adjoining or contiguous to the first-named tank, and provided with an outlet, a vessel pivoted in the last-named tank,

a channel at or along one side of said vessel, said channel or gutter provided with an opening, a float beneath the channel or gutter, a pipe connecting the two tanks, and having its discharge end passing into the pivoted vessel, and a siphon having its legs extending into the respective tanks, substantially as set forth. 20

In testimony whereof I affix my signature in presence of two witnesses.

FRANK C. KELLER.
